UNITED STATES PATENT OFFICE

WALTER BARCHARD, OF CHICAGO, ILLINOIS.

DESIGN FOR A HOT-WATER HOLDER.

SPECIFICATION forming part of Design No. 29,026, dated July 12, 1898.

Application filed June 3, 1898. Serial No. 682,491. Term of patent 7 years.

To all whom it may concern:

Be it known that I, WALTER BARCHARD, a citizen of the United States, residing at Chicago, in the county of Cook and State of Illinois, have invented and produced a new and original Design for Hot-Water Holders, of which the following is a specification, reference being had to the accompanying drawings, forming part thereof.

10 Figure 1 is a perspective view of a hot-water holder, showing my new design; and Fig. 2 is a view in side elevation thereof.

As shown in the drawings, the leading or material feature of my design consists of a 15 hollow vessel A, oval in outlines and having its upper and lower surfaces curved in parallelism. The sides of the vessel are inclined

inwardly or toward the bottom, as shown at a in Fig. 2 of the drawings, and located on its upper surface is a handle B, which extends 20 longitudinally with the vessel and is slightly inclined toward one side thereof. Between the handle B and the side of the vessel and located in the top thereof is a tubular portion b, in which fits a plug c, having a milled rim. 25

Having described my invention, what I claim as new, and desire to secure by Letters Patent, is—

The design for a hot-water holder as herein shown and described.

WALTER BARCHARD.
